AUTOMATIC TELEPHONE SYSTEM

Leonard Wilson, Salt Lake City, Utah, assignor, by mesne assignments, to Milton S. Friendly, Chicago, Ill., Oscar N. Friendly, Salt Lake City, Utah, and Central Republic Trust Company, Chicago, Ill., a corporation of Illinois, trustees under the will of Herbert M. Friendly, deceased

Application January 30, 1932, Serial No. 589,829

30 Claims. (Cl. 179—7.1)

The present invention relates in general to automatic telephone systems and more particularly to measured service automatic systems.

One of the objects of the present invention is to provide a novel zone metering system in which a charge is made in accordance with the distance between subscribers.

Another object is to provide means whereby the zone metering charge may be assessed against the called subscriber's telephone.

Another object is to provide mechanism by which the called subscriber can reverse the periodical metering charge from the calling subscriber's line to his own irrespective of whether the calling and called subscribers are in the same exchange or not.

Another object is to provide mechanism whereby this reversal may be made by the called subscriber at any time during his conversation with the calling subscriber.

Another object is to provide a method of making a charge to the line of the called subscriber at his option in accordance with the length of the conversation and also in accordance with the inter-exchange trunk lines employed for the conversation.

A further object is to provide mechanism whereby the zone metering charge on either the calling or called subscriber's line or both is dependent not only upon the trunk lines employed for establishing the connection but depends upon the telephone traffic load in the exchanges.

A further object is to provide mechanism for rendering it impossible to reverse the zone metering charges in telephone connections with a restricted class of called subscribers.

A still further object is to apprise the subscribers, irrespective of whether they are located in the same exchange or not, of the line to which the charge is being made.

Still another object is to provide a translating device which may be associated with the inter-exchange trunk line or any other trunk line that will serve to add to the usual metering charge a charge for the use of the inter-exchange trunk.

A still further object is to accomplish the foregoing results over two wire inter-exchange trunk lines in a simple and highly expeditious manner.

There are other objects of my invention which, together with the foregoing, will be described in the detailed specification that is to follow taken in conjunction with the accompanying drawings and forming a part thereof.

The present invention is an improvement on

the co-pending application of Herbert M. Friendly, Serial No. 575,135, filed November 14, 1931.

My invention has been illustrated in an automatic telephone system of the so-called Strowger type employing first and second selectors and connectors. Obviously, a greater number of selectors may be employed if necessary or desirable to provide a greater number of subscribers. That is, third and fourth selectors may be employed in each exchange if it is desired, to provide for

selection in a ten thousand (10,000) line exchange with selection between any one of one hundred (100) exchanges making a total capacity for the whole system of a million (1,000,000) lines. The manner in which the trunking capacity of the system can be increased or altered is well-known and need not be described. In practicing the invention, a metering device is provided for each line which it is desired to make a charge against.

A timing switch is associated with each first selector and with each connector in order to bring about the timing of the conversation. A mechanism is associated with each interexchange trunk line at both the incoming and outgoing ends to assess additional charges for the use of trunks employed in the connections. This arrangement

limits the additional charging mechanism to use on interexchange calls only where the distance between subscribers is greater and more equipment is employed. While the invention has been illustrated in connection with one way inter-office trunk lines, it will be obvious that it may be employed in connection with two-way trunk lines.

A push button is provided at each subscriber's telephone so that when that telephone is called by the called subscriber thereat may reverse the charge.

Briefly, the operation of my invention proceeds as follows:

The connection between the calling and called subscriber is accomplished in the usual manner through the calling subscriber's line switch, an idle first selector, an idle second selector and a connector. When the subscribers are connected, the timing switch individual to the first selector is operated periodically to actuate the meter associated with the calling subscriber's line. In the event the called subscriber is one of those subscribers who may reverse the charges he presses the push button at his telephone, which brings about the cessation of the operation of the timing switch at the first selector and the initiation of the operation of the timing switch individual to the connector. The operation of the timing switch individual to the connector causes

the meter associated with the called subscriber's line to be actuated periodically. Audible signals are applied to the line at short intervals before the charge is made, the tone being of one pitch 5 to inform the called subscriber if the charge is being made against him and of another pitch to inform the calling subscriber if the charge is being made against him. The foregoing is the operation of a call between subscribers, local to the 10 same exchange. In the event the connection is one between lines located in different exchanges, the connection is accomplished in the usual manner, including the calling subscriber's line switch, an idle first selector, a repeater associated with a 15 trunk line extending to the distant exchange, an incoming second selector at that exchange and an idle connector switch. When the connection is established, the timing switch individual to the first selector is operated periodically to actuate 20 the meter associated with the calling subscriber's line. At each metering charge by the timing switch associated with the first selector the meter adding device associated with the repeater employed in the connection brings about an additional charge according to the distance between 25 exchanges.

In the event the called subscriber is one of those subscribers who may reverse the charges from the calling line to his own, he presses the push button at his telephone which brings about the cessation 30 of the operation of the timing switch at the first selector and the effective operation of the timing switch individual to the connector. The operation of the timing switch individual to the connector causes the meter associated with the called subscriber's line to be actuated periodically. After each metering impulse, the timing mechanism associated with the trunk line at its incoming end in the exchange local to the 35 called subscriber is effective to bring about an additional metering charge in accordance with the distance between exchanges. In this manner a charge is made to either the calling or called telephones in accordance with the amount of 40 equipment employed for the connection and the distance between the various exchanges in the system. That is, a zone metering charge is made dependent not only on the distance but on the time employed for the conversation. As will 45 appear more fully hereinafter, another variation of the charge can be made dependent upon the traffic load or the time of day at which the call is made. Audible signals are applied to the connection between the subscribers to indicate 50 when the charge is being made and also to differentiate as to the line the charge is being made against.

Referring now to the drawings comprising Figs. 1 to 5, inclusive, the invention has been 55 illustrated in connection with a simple hundred thousand (100,000) line automatic telephone system of a step by step or Strowger type, wherein the apparatus and circuits are shown by means of the usual conventional diagrams. The sheets are arranged to illustrate the connection between a called and calling subscriber when placed side by side with the similarly numbered conductors in alignment.

In Fig. 1 in the upper left hand corner of the 60 sheet a calling subscriber's telephone is illustrated, designated with the reference character T. The telephone comprises the usual transmitter, receiver, switch hook and ringer. In addition, the telephone is provided with a push button 102 whose contacts normally short circuit a

resistor included in the line circuit. Reference character LS designates the usual type of rotary line switch individual to the line of the subscriber at sub-station T. The line switch is provided with the usual line relay 109, switching relay 108 and motor magnet 114. The motor magnet 114 is operated to advance the switch wipers 110 to 113, inclusive, step by step over associated bank contacts such as 121 to 124, inclusive, in search of an idle trunk. A metering device 107 of any usual or well known type is associated with each line switch. The rotary switches LS have access to trunk lines extending to first selectors such as the first selector S.

The selector S is generally of the usual and well known Powell type, having controlling relays 125 to 132, inclusive, and being provided with the usual vertical magnet 133, rotary magnet 134, and release magnet 135. The selector S has access to 10 groups of trunk lines terminating in 10 20 groups of bank contacts 184 and 187, inclusive, accessible to switch wipers 135 to 138, inclusive. A rotary timing switch RS-1, which may be of the same general mechanical construction as the rotary switch LS, is associated with each first 25 selector such as S. The rotary switch RS-1 has access to bank contacts which are connected to metering and tone machine mechanism M. The metering and tone machine mechanism M is common to all the metering switches, such as 30 RS-1, associated with the first selector S. This metering equipment consists essentially of two motor driven shafts 174 and 181, upon which are mounted commutating segments 172 and 173 and 35 175 to 178, respectively. The commutating segments 172, 173, 177 and 178 are connected to the battery, while the commutating segments 175 and 176 go to tone machines and may generate audible signals of different pitch.

The trunk lines terminating in the bank contacts accessible to the first selectors such as S extend to other selectors and also the trunk lines extending through repeaters such as R (Fig. 2) to incoming second selectors such as S-1 (Fig. 3) at a distant exchange. Repeaters such as R are 40 generally of the same type as those ordinarily employed in automatic exchanges and are provided with controlling relays 250 to 254, inclusive. A rotary timing switch RS-5 is associated with the trunk line extending to each repeater such as R and is provided with controlling relays 200 to 202, inclusive, a motor magnet 218, and switch wipers 212 to 214, inclusive. The rotary switch RS-5 is a timing switch and its switch wipers are adapted to engage a plurality of bank 45 contacts which may be twenty-five in number in the event the switch is similar to the usual rotary line switches.

The motor magnet 218 is adapted to step the switch wipers 212 to 215, inclusive, into engagement with the associated bank contacts. An interrupter 225 is adapted to control the operation of the motor magnets of the various switches as will appear. The incoming second selector S-1 is of the usual and well known type or Strowger 50 switch commonly known as the Powell type, being provided with a vertical magnet 320, rotary magnet 321, release magnet 322 and control relays 315 to 319, inclusive. The selector S-1 is also provided with wipers 336 to 339, inclusive, which 55 have access to bank contacts in ten (10) levels. The trunk lines connected to these bank contacts may extend to connectors such as C (Fig. 4) of the usual step by step type.

A rotary timing switch RS-6 is associated with 75

each of the incoming selectors such as S-1 and generally is of identically the same construction as the rotary timing switch RS-5 (Fig. 2) previously described. This switch is provided with control relays 350 to 352, inclusive, motor magnet 368 and switch wipers 262 to 264, inclusive, adapted to engage the associated bank contacts.

The connector C is provided with control relays 400 to 410, inclusive, and the usual vertical magnet 412, rotary magnet 413, and release magnet 411. The connectors such as C are divided into 10 groups, each group having access to 100 subscriber's lines. Thus the connector C has access through the wipers 416 to 419, inclusive, and bank contacts such as 492 to 495, inclusive, to the lines of 100 subscribers. A timing switch RS-2 is individual to each connector. This switch may be of the same general mechanical construction as the switch LS previously described, having a motor magnet 464 for advancing the switch wipers 473 to 476, inclusive, about its associated bank contacts. The bank contacts of the timing switch are connected to common metering equipment M-2. The metering equipment M-2 consists essentially of two motor driven shafts 488 and 489, which are provided with the commutating segments 482, 483, 484 and 487 and 485 and 486, respectively. The commutating segments 484, 487, 485 and 486 are connected to the battery, while the commutating segments 482 and 483 are connected to tone machines capable of generating signals of different pitch. In addition, a common metering device M-1, which consists of a clock driven wiper 461 adapted to engage circular contacts twenty four in number, for each hour of the day. The wiper 461 will be in engagement with a certain particular contact.

As before mentioned, the connector C has access to called telephone lines of 100 called subscribers, such as the subscribers located at stations T-1 to T-3, inclusive. Each of the called subscriber's lines is provided with rotary line switches such as RS-3 of identically the same construction as the rotary switch LS previously described. The telephone sub-station circuits of the called subscribers such as T-1 are of identically the same construction as the telephone sub-station T previously described, being provided with the usual transmitter, receiver, switch hook and ringer, and, in addition, push button 556 and resistor 555. A slightly modified form of sub-station circuit is shown at T-2, wherein the push button 557 is employed to ground one side of the line. The circuit of the telephone sub-station T-3 is of the usual type, not being provided with a push button. This is to illustrate the line of a called subscriber who has free service. The line of the sub-station T-3, in addition to terminating in the contacts of the connector C and other connectors of the same group, terminates in the rotary line switch RS-4. In addition relays, such as 517 to 519, are provided in association with this line for the purpose of preventing the telephone subscriber at station T-3 from altering the metering charge of the calling subscriber when in connection with his line in any manner.

While the timing switches RS-1 and RS-2, RS-5 and RS-6 associated with the first selector S, repeater R, incoming selector S-1 and connector C, respectively, have been illustrated as individual to these switches, it will be understood that they may be made common to a group of their respective switches by the use of finder switches in any suitable or well known manner.

Having briefly described the apparatus and

circuits shown in the drawings, their detailed operation will now be described. For this purpose, it will be assumed that the subscriber at sub-station T desires to call the subscriber at sub-station T-1. In order to accomplish this result the subscriber at sub-station T will remove his receiver from the switch hook, thereby completing a circuit which extends from ground by way of back contact and armature 117, line conductor 101, contacts of push button 102, switch hook contacts, receiver and transmitter in series, line conductor 100, armature 116 and its back contact, winding of line relay 109, and thence to battery. The slow acting relay 109 is energized over this circuit and serves to complete a circuit which extends from ground by way of armature 120 and its front contact, switching relay 108, back contact and armature of motor magnet 114, and then through the winding of this magnet to battery, and at armature 119 and its front contact serves to connect the test wiper 111 to the above circuit at a point midway between the switching relay 108 and motor magnet 114. In the event that the switch wipers 110 to 113, inclusive, are in engagement with a busy trunk line, ground will be connected to the bank contact associated with the test wiper 111, and the motor magnet 114 will be operated to advance the switch wipers 110 to 113, inclusive, until they are in engagement with the bank contacts associated with an idle trunk line. At this time there will be a circuit completed for the switching relay 108 in series with the motor magnet 114. The switching relay 108 upon operating connects the meter 107 to the metering wiper 110 at armature 115 and its front contact, opens the test circuit of the motor magnet 114 at armature 118 and at the front contact of this armature prepares a holding circuit for the switching relay 108. At armatures 116 and 117 the operation of the switching relay 108 serves to open the circuit of the slow acting line relay 109 and to extend the talking conductors 100 and 101 to the wipers 112 and 113. It will be assumed that the trunk selected by the operation of the line switch is the trunk line terminating in the bank contacts 121 to 124, inclusive. Consequently, upon the extension of the talking conductors 100 and 101 as described there will be a circuit completed extending from ground through the lower winding of the line relay 129, of the selector S, back contact and armature 146, bank contact 124, thence through the calling subscriber's telephone, bank contact 123, through the lower winding of the electropolarized relay 127, armature 147 and its back contact, and thence through the upper winding of the line relay 129 to battery. The line relay 129 is energized over this circuit and upon operating opens a point in the circuit of the release magnet 135 at armature 150 and its back contact, and at the front contact of this armature completes a circuit for the slow acting relay 130. The slow acting relay 130 upon operating disconnects ground from certain bank contacts in the timing switch RS-1 at armature 151 and its back contact, at the front contact of this armature connects ground to the holding or release trunk conductor, and at armature 152 and its front contact prepares a circuit for the vertical magnet 133. The connection of ground to the release trunk conductor serves to establish a holding circuit extending back to the switching relay 108 of the rotary switch LS and the motor magnet 114 in series, in order to maintain the switching relay 108 energized after the deenergization of the slow acting line relay 109.

The application of ground to the release trunk also completes the circuit for the polarizing winding of the electro-polarized relay 127.

When the calling subscriber at sub-station T 5 operates his calling device CD in accordance with the first digit of the called subscriber's number a series of interruptions are produced in the circuit of the line relay 129 which retracts its armature a number of times corresponding to the 10 number of interruptions. At each retraction of its armature 150 there is a circuit completed which extends from ground by way of armature 150 and its back contact, back contact and armature 149, armature 152 and its front contact, winding of slow acting relay 131, and vertical magnet 133 to battery. The vertical magnet is 15 operated to raise the switch wipers 135 to 138, inclusive, opposite the proper level of the bank contacts. At the first off normal step of the 20 switch, the off normal springs 156 and 157 are shifted to prepare a circuit for the rotary and release magnets. The slow acting relay 131 is energized to open a point in the circuit of the rotary magnet 134 at armature 153, and to complete a 25 circuit which extends from ground by way of armature 151 and its front contact, armature 153 and its front contact, armature 194 and its back contact, working contact of off normal spring 155 and said spring and interrupter relay 132 to battery. The interrupter relay 132 is energized over 30 this circuit to establish a locking circuit for itself at armature 154 and to prepare the circuit for the rotary magnet 134 at armature 155.

A short interval after the calling device has 35 returned to normal position the relay 131 is de-energized to complete a circuit for the rotary magnet 134 over a path that extends from ground by way of armature 151 and its front contact, armature 153 and its back contact, armature 155 and its front contact, and rotary magnet 134 to battery. The rotary magnet 134 is energized over 40 the above circuit and operates to advance the switch wipers 135 to 138 inclusive, one step into engagement with the first set of bank contacts 45 on the level selected. A further result of the operation of the rotary magnet 134 is that at armature 194 the circuit of the interrupter relay 132 is opened and it de-energizes. The de-energization of the interrupter relay 132 opens a point 50 in the circuit of the rotary magnet at armature 155 and at armature 154 opens a point in its locking circuit. A test circuit is now established, which extends from the test wiper 136 by way of armature 146 and its back contact, armature 194 and its back contact, working contact of off-normal spring 156, and said spring and relay 132 to battery. If the trunk line with which the switch wipers 136 to 138, inclusive, are in engagement is busy, there will be a ground potential 55 upon the bank contact engaged by the switch wiper 136 and the relay 132 will be energized over the above circuit to establish a locking circuit for itself at armature 154 and to complete a circuit for the rotary magnet at armature 155. The 60 rotary magnet 134 upon operating opens the circuit of the interrupter relay 132, which is de-energized to interrupt the circuit of the rotary magnet. The alternate operation of the interrupter relay 132 and the rotary magnet 134 continues until the switch wipers 135 to 138, inclusive, are advanced into engagement with the bank contacts associated with an idle trunk line, which it will be assumed are the bank contacts 184 to 187, inclusive. When the switch wipers are 65 brought into engagement with this set of bank

contacts there will be no ground potential upon the bank contact 185 and no circuit will be completed for the interrupter relay 132. The circuit is now established which extends from ground by way of armature 151 and its front contact, winding of switching relay 128, armature 194 and its back contact, working contact of off-normal spring 156 and said spring and interrupter relay 132 to battery. On account of the high resistance of the relay 128, the interrupter relay 132 is not operated over this circuit. The switching relay 128 upon operating opens the point in the circuit of the release magnet at armature 149, opens a point in the testing circuit at armature 146, and at armatures 147 and 148 disconnects the talking circuit extending to the calling telephone from the windings of the line relay 129 and at the front contacts of these armatures extends the calling line through the wipers 137 and 138, bank contacts 186 and 187, trunk conductors 197 and 198, normally closed springs controlled by armatures 260 and 261, to the upper and lower windings of the line relay 251 of the repeater R. 15

The line relay 251 of the repeater R is energized over a circuit including the calling line and operates to complete a circuit for the slow acting relay 252 at armature 263 and to complete a bridge across the trunk conductors 280 and 281 at armature 264. The slow acting relay 252 is energized to prepare a circuit for the slow acting relay 253 at armature 268 to complete another point in the bridge circuit across the trunk conductors 280 and 281 at armature 266 and to complete the circuit for the polarizing winding of the electro polarized relay 254 at armature 267. A further result of the operation of the relay 252 is that at armature 267 there is a holding circuit established for the switching relay 128 of the selector S and the holding relay of the line switch LS. This holding circuit is established prior to 40 the de-energization of the slow acting relay 130 of the selector S which occurs a short interval of time after the de-energization of the line relay 129 following the operation of the switching relay 128. 45

The bridge across the trunk conductors 280 and 281 establishes a circuit for the line relay 316 of the incoming selector S—I over a path that may be traced from ground, lower winding of line relay 316, back contact and armature 325, trunk conductor 281, front contact and armature 264, right-hand winding of impedance relay 258, normally closed springs controlled by armature 262, winding of electro-polarized relay 254, normally closed springs controlled by armature 269, front contact and armature 266, trunk conductor 280, armature 324 in its back contact and upper winding of line relay 316 to battery. The line relay 316 is energized over this circuit in the incoming selector S—I and operates to complete 60 a circuit at armature 327 for the slow acting relay 317. The slow acting relay 317 is energized to open a point in the circuit of the release magnet 322 at armature 329 and to prepare a circuit for the vertical magnet 320 at the front contact of 65 this armature.

Another result of the operation of the relay 317 is that at armature 328, a circuit is prepared for the switching relay 315 and for the rotary magnet 321. 70

When the calling device at the sub-station A is operated in accordance with the next digit of the called subscriber's number, which it will be assumed is the digit 2, two interruptions will be produced in the circuit of the line relay 251 of 75

- the repeater R and this relay will be operated to retract its armatures 263 and 264 twice. At each retraction of the armature 263 there is a circuit completed for the slow acting relay 253.
- 5 The slow acting relay 253 is energized to change the bridge across the trunk conductors 280 and 281, excluding the windings of the relays 258 and 254, the bridge extending from conductor 281, front contact and armature 264, armature 269 and its front contact, front contact and armature 256 to trunk conductors 280. At each retraction of the armature 264 this bridge circuit which includes the line relay 316 of the incoming selector S-1 is interrupted.
- 10 At each retraction of the armature 327, there is a circuit completed which extends from ground by way of said armature and its back contact, back contact and armature 326, armature 329 and its front contact, slow acting relay 318 and vertical magnet 320 to battery. The vertical magnet is operated to raise the switch wipers 336 to 339 inclusive two steps opposite the second level of bank contacts. The slow acting relay 313 is energized in series with the vertical magnet 320 and operates to complete a circuit which extends from ground by way of front contact and armature 323, armature 332 and its front contact off-normal spring 331 and its working contact and interrupter relay 319 to battery. The interrupter relay is energized at the first off-normal step of the switch to prepare a circuit for the rotary magnet 321 at armature 335 and to establish a locking circuit for itself at armature 334. A short interval after the cessation of the operation 15 of the line relay 316 the slow acting relay 318 is de-energized to complete a circuit for the rotary magnet at armature 332 and its back contact. The rotary magnet 321 is energized to advance the switch wipers 336 to 339 inclusive, into engagement with the first set of bank contacts on the second level. The rotary magnet also brings about the opening of the locking circuit of the relay 319 at armature 333. Relay 319 is de-energized to open the circuit of the rotary magnet 321 which is also de-energized. If the bank contacts engaged by the switch wipers 336 to 339 inclusive, are associated with a busy trunk line, there will be a ground potential present upon the test contact engaged by the 20 switch wiper 337 and there will be a circuit completed extending from said ground armature 323 and its back contact, back contact and armature 333, off-normal spring 331 and its working contact and interrupter relay 319 to battery. The interrupter relay 319 will be energized over this circuit to establish a locking circuit for itself at armature 334 and to complete a circuit at armature 335 for the rotary magnet 321. The rotary magnet 321 is energized to advance the 25 switch wipers into engagement with the next set of bank contacts and to open the circuit of the interrupter relay 319. The interrupter relay 319 and the rotary magnet 321 continue to operate alternately until the switch wipers 336 to 339, inclusive, are brought into engagement with the bank contacts associated with an idle trunk line which it will be assumed are the bank contacts 341 to 343, inclusive. In this instance there will be no ground potential present upon the bank contact 341 and no circuit will be completed for the interrupter relay 319. A circuit is now effective for the switching relay 315 which extends from ground by way of front contact and armature 328, relay 315, back contact and armature 333, off-normal spring 331 and its working con- 30 tact and relay 319 to battery. The switching relay 315 is the only one operatively energized over the above circuit because of its high resistance. The relay 315 upon operating opens a point in the circuit of a release magnet 322 at armature 326, prepares the locking circuit for itself at armature 323, and at armatures 324 and 325 disconnects the line of the sub-station A from the windings of the line relay 316 and extends them by way of the front contacts of these armatures, wipers 338 and 339, bank contacts 342 and 343, conductors 397 and 398 through normally closed springs controlled by armatures 427 and 428 on relay 403 of the connector C, and thence to the upper and lower windings of the line relay 404 of the connector. The line relay 404 is energized over a circuit, extending to the repeater R-2, and upon operating opens a point in the circuit of the release magnet at armature 431 at its back contact and at armature 431 and its front contact completes a circuit for the slow acting relay 405. The slow acting relay 405 upon operating opens a further point in the circuit of the release magnet at armature 433 and its back contact prepares a circuit for the vertical magnet at the front contact of this armature, disconnects ground from certain bank contacts in the timing switch or at armature 432 at its back contact, and at the front contact of this armature prepares a locking circuit for certain other relays. The 35 operation of the relay 405 also connects ground to the release trunk conductor 395, whereby a locking circuit is established extending by way of this conductor, bank contact 341, test wiper 337, armature 323 and its front contact, relay 316, back contact and armature 333, working contact of off-normal spring 331 and its working contact relay 319 to battery.
- This holding circuit is established prior to the de-energization of the slow acting relay 317, 40 which occurs a short interval of time after the de-energization of the line relay 316 following the operation of the switching relay 315 previously described.
- In the repeater R a short interval of time after 45 the restoration of the calling device at calling sub-station T to normal, the slow acting relay 253 is de-energized to restore the bridge across the trunk conductors 280 and 281 in the repeater R to include the windings of the relays 254 and 258.
- When the calling subscriber at sub-station T operates his calling device in accordance with the next digit of the called subscriber's number a series of interruptions will be produced in the 50 circuit of the line relay 251 of the repeater R. By the operation of the line relay 251 a corresponding number of interruptions will be produced in the circuit of the line relay 404 of the connector C.
- This relay will be de-energized a plurality of times. At each de-energization of the line relay 404 there is a circuit established, which extends from ground by way of armature 431 and its back contact, armature 433 and its front contact, resting contact of off-normal spring 458 and said spring relay 406 and vertical magnet 412 to battery. The vertical magnet 412 is operated to raise the switch wipers 416 to 419, inclusive, opposite the level of bank contacts cor- 55 responding to the digit of the called subscriber's number that has been dialed. The slow acting relay 406 is energized in series with the vertical magnet 412 and serves to prepare a new circuit for the vertical magnet 412. At the first off- 60
- 75

normal step of the switch the circuit of the vertical magnet is changed and may be traced over a path extending from ground by way of armature 431 and its back contact, armature 433 5 and its front contact, off-normal contacts 415, armature 434 and its front contact, relay 406 and vertical magnet 412 to battery.

A short interval of time after the calling subscriber's calling device restores to normal, the 10 slow acting relay 406 is de-energized to open a point in the circuit of the vertical magnet 412 and to prepare a circuit for the rotary magnet 413.

In the repeater R, a short interval of time 15 after the cessation of the operation of the line relay 251, the slow acting relay 253 is de-energized to restore the original bridge across the cross conductors 280 and 281.

When the calling subscriber operates his calling device in accordance with the last digit of 20 the called subscriber's number, there will be another series of interruptions produced in the circuit of the line relay 251 of the repeater R. The line relay 251 of the repeater will retract 25 its armatures 263 and 264 a corresponding number of times. By the operation of the armatures 263, the slow acting relay 253 will be energized to charge the bridge across the trunk conductors in the manner described. By the operation of the 30 armatures 264 a plurality of interruptions will be produced in the bridge across the trunk conductors 280 and 281 bringing about the de-energization of the line relay 404 of the connector C in the distant exchange a plurality of times. 35 At each de-energization of the line relay 404 there is a circuit completed, which extends from ground by way of armature 431 and its back contact, armature 433 and its front contact, off-normal springs 415, armature 434 and its back contact, back contact and armature 441, back contact and armature 454, and rotary magnet 413 to battery. A branch of this circuit extends through the slow acting relay 409 to battery. The rotary magnet 413 is operated a plurality of 40 times to advance the switch wipers 414 to 417, inclusive, into engagement with the bank contacts associated with the line of the subscriber at sub-station T-1, which it will be assumed are the bank contacts 492, 496, 494 and 45 498, respectively. The slow acting relay 409 is energized in parallel with the rotary magnet 413 and operates at armature 443 to prepare a circuit for the busy test relay 408 and to prepare an alternative circuit for itself and the rotary magnet at armature 444 and its front contact, exclusive of the armature 441. This result is for 50 the purpose of maintaining the circuit of the rotary magnet, irrespective of the energization of the busy test relay 408 in the switch wipers 416 to 419 passing over busy lines. This result is brought about by the test wiper 417 encountering a ground potential upon bank contacts it rotates over, and bringing about the operation of 55 the relay 408.

65 It will first be assumed that the line of the called subscriber at sub-station T-1 is busy. In this instance there will be a ground potential applied to the bank contact 496, and when the test wiper 417 is brought into engagement with 70 this bank contact a circuit will be established extending to the busy test relay 408. The busy test relay 408 upon operating prepares a locking circuit for itself at armature 440, opens a point in the rotary magnet circuit at armature 441, 75 and at armature 442 applies the busy tone to a

conductor extending to the calling telephone. A short interval after the cessation of the last series of impulses the slow acting relay 409 is de-energized to open another point in the rotary magnet circuit at armature 444 and to establish the locking circuit of the relay 408 at the normally closed springs controlled by armature 443. This locking circuit may be traced from ground by way of front contact and armature 414, armature 440 and its front contact, normally closed 8 springs controlled by armature 443, armature 452 and its back contact and relay 408 to battery. 10

At the repeater R, a short interval of time after the calling device at the calling sub-station restores to normal the slow acting relay 253 is de-energized to restore the bridge across the trunk conductors 280 and 281 to its normal condition. 15

When the calling subscriber hears the busy signal, he will replace his receiver upon the switch hook, thereby bringing about the de-energization 20 of the line relay 251 in the repeater R. As a result of the de-energization of this relay, the circuit of the slow acting relay 252 is opened at armature 263 and the bridge across the trunk conductors 280 and 281 is opened at armature 264. 25 As a result of the opening of the bridge, the line relay 404 in the connector C at the distant exchange will be de-energized. Immediately upon the de-energization of the slow acting relay 252 in the local exchange, ground will be removed 30 from the release trunk conductor 196 thereby opening the circuits of the switching relays 128 of the selector S and 108 of the line switch LS. In the selector switch S the switching relay 128 is de-energized to complete a circuit for the release magnet 135 over a path which extends from ground by way of armature 150 and its back contact, back contact and armature 149, armature 152 and its back contact, working contact of off-normal spring 157 and said spring, switch 35 wiper 160 of timing switch RS-1, first bank contact, and release magnet 135 to battery. The release magnet 135 is energized to restore the switch wipers 136 to 138 to normal. The disconnection of ground from the release trunk conductor 196 also brings about the de-energization 40 of the switching relay 108 of the rotary line switch RS, which upon de-energizing connects the calling line to the line relay 109 so as to prepare 45 the rotary line switch for another call. 50

At the distant exchange, the line relay 404 is de-energized to retract its armature 431. A short interval after the retraction of the armature 431, the slow acting relay 405 is de-energized to complete a circuit for the release magnet over a path 55 which may be traced from ground by way of armature 431 and its back contact, armature 433 and its back contact, armature 423 and its back contact, off-normal spring 457 and its working contact, back contact and armature 471 and release magnet 411 to battery. The release magnet 411 is energized to restore the switch wipers 416 to 419, inclusive, to their normal position in the usual manner. The de-energization of the slow acting relay 405 also disconnects ground from 60 the release trunk conductor 396 thereby opening the holding circuit of the switching relay 315 of the incoming selector switch S-1. The relay 315 is de-energized to complete a circuit for the release magnet 322 at armature 326 over a path 65 that extends from ground by way of armature 327 and its back contact, back contact and armature 326, armature 329 and its back contact, working contact of off-normal spring 330 and release magnet 322 to battery. The release magnet 322 is 70 75

energized to restore the switch wipers 336 to 339, inclusive, to normal at which time the circuit of the release magnet 322 is opened at the off-normal spring 330.

- 5 In the foregoing manner, the switches involved in the establishment of the connection between the sub-stations T and T-1 are restored to normal responsive to the replacement of the receiver at the calling station.
- 10 It will now be assumed that the line of the sub-station T-1 when called by the subscriber at sub-station T was idle. In this instance when the switch wipers 416 to 419 inclusive, of the connector C are brought into engagement with the bank contacts 492, 496, 494 and 498, there will be no ground potential upon the test contact 496 and no circuit will be completed for the busy test relay 408. Now a short interval after the calling device CD at the calling sub-station T is restored to normal, the slow acting relay 409 will be de-energized to complete a circuit for the switching relay 410 over a path which extends from ground by way of front contact and armature 414, armature 440 and its back contact, lower winding of relay 410, back contact and armature 443, test wiper 417, bank contact 490, conductor 505, relay 546, back contact and armature 558, and motor magnet 544 to battery. The switching relay 410 is energized over this circuit and operates to establish a locking circuit for itself at armature 453 to open a point in the locking circuit of the busy test relay 408 at armature 452 to open a point in the circuit of the rotary magnet at armature 454 to apply ground to the test wiper 417 at armature 455 and to complete the ringing circuit at armatures 450, 451 and 456. The application of ground to the busy test wiper applies a full ground potential to the conductor 505 to busy the called line.
- 40 The switching relay 546 in the line switch RS-3 associated with the called sub-station T-1 is energized, but by reason of an inter-locking device controlled by the armature of the line relay 545, the armatures 547, 548, 549 and 551 are only partially operated sufficient to dis-engage their back contacts but not to engage their front contacts. In this manner the called line is cleared of attachments. A ringing circuit is now established which extends from ground by way of back contact and armature 439, front contact and armature 456, wiper 419, bank contact 498, conductor 507 over the line of the called telephone through its ringer, condenser, switch hook, springs of push button 506, over line conductor, conductor 502, bank contact 484, wiper 418, armature 450 and its front contact, armature 436 and its back contact, upper winding of ring cut-off relay 407 and thence to battery either through the ringing generator R or the armature 491 and its back contact. The relay 407 is not operated by the alternating current passing over this circuit. Ringing current is intermittently applied to the called line until the subscriber at sub-station T removes his receiver, whereupon there is a circuit for direct current over the line of the called telephone and the relay 407 is energized to establish a locking circuit for itself at armature 437. This locking circuit is established before any other armature or springs of the relay are operated. The relay 407 upon operating opens a point in its own energizing circuit at armature 438 at the front contact of this armature, completes a point in the circuit of a supervisor signal at armature 438, opens a point in the ring-
- 5 ing circuit at armature 439 and at the front contact of this armature completes the talking circuit. The talking circuit extends to the called telephone over the heavy conductors shown in the drawings. The calling telephone is supplied with talking current through the windings of the line relay 251 in the repeater R while the called telephone is supplied with talking current through the windings of the relays 400 and 401 over a circuit which may be traced from ground through the lower winding of the marginal relay 401, lower winding of back bridge relay 400, front contact and armature 439, front contact and armature 456, wiper 419, bank contact 498, conductor 501, called telephone line, conductor 502, 10 bank contact 494, wiper 418, armature 450 and its front contact, armature 436 and its front contact, upper winding of back bridge relay 400 and upper winding of marginal relay 401 to battery. The back bridge relay 400 and the marginal relay 20 401 are energized over this circuit. The relay 401 upon operating prepares a point in the circuit of the differential relay 403 at armature 424 and at armature 425 opens a point in the circuit of the upper winding of this relay. The relay 400 25 upon operating opens a point in the circuit of a supervisory signal at armature 420, and its back contact, and at the front contact of this armature establishes a further locking circuit for the switching relay 410, completes a circuit for the 30 lower winding of the differential relay 403 at armature 421, and at armature 422 prepares a circuit for the upper winding of the differential relay. Another result of the operation of the relay 400 is that at armature 423 a point in the 35 circuit of the release magnet is opened and at the front contact of this armature a point in the circuit of a supervisor signal is established. The circuit for the lower winding of the differential relay 403 may be traced from ground by way of 40 front contact and armature 414, armature 421 and its front contact, armature 424 and its front contact, and lower winding of differential relay 403 to battery. The differential relay 403 is energized over this circuit to establish a locking 45 circuit for its lower winding at armature 429 to complete a circuit for the motor magnet 464 of the timing switch RS-2 at armature 430 and to reverse the connections of the line relay 404 with respect to the trunk conductors 397 and 398 50 at armatures 427 and 428, respectively. The reversal of the connections of the line relay as described bring about the operation of the timing switch RS-1, associated with the selector S as will be explained. The circuit for the motor magnet 464 may be traced from ground by way of 55 front contact and armature 414, armature 430 and its front contact, the bank contact with which the switch wiper 475 is in engagement when the switch RS-2 is in normal or initial position, 60 switch wiper 475, back contact and armature 465, and motor magnet 464 to battery. The motor magnet 464 is operated over this circuit to advance the switch wipers 473 to 476, inclusive, of the timing switch RS-2 into engagement with 65 the second set of bank contacts. The operation of the timing switch RS-2 is thus initiated by the response of the called party at sub-station T-1, but its operation has no particular function at the present time and the description of 70 its operation will be left until it does function, which occurs when the charge is to be assessed against the called line.
- 75 It is to be noted at this time that when the switch wipers 416 to 419, inclusive, of the con-

necter switch C are brought into engagement with the bank contacts associated with the called line of the sub-station T-1, there was a circuit completed for the high resistance relay 402, if 5 this call was made at certain periods of the day. This depends upon the operation of the clock switch M-1, which may be of any usual or well known type. It will be seen that the wiper 461 of the switch M-1 is adapted to connect battery 10 to the common conductor 446, if the common conductor is tapped into certain bank contacts representing the hours of the day. Consequently, the periods during which battery is applied to this conductor may be regulated. The connection 15 of battery to this conductor determines whether or not the called party may reverse the charge by the use of instrumentalities at his sub-station. If battery is not connected to this conductor, he cannot alter the charge being assessed to the 20 calling line. This may be desirable at certain periods of the day, as warranted by traffic conditions.

It will be assumed in the present instance, however, that at the time the switch wipers of 25 the connector were brought into engagement with the bank contacts of the called line battery was connected by the clock switch M-1 to the common conductor 446. In this instance, there is a circuit completed for the relay 402, which 30 extends from battery through the winding of the relay 402, front contact and armature 445, switch wiper 416, bank contact 492, conductor 500, meter 552 of the called line, associated with switch RS-3 to ground. The meter 552 is not 35 operated over this circuit by reason of the high resistance of the relay 402. However, this relay is energized to prepare a circuit for the upper winding of the differential relay 403 at armature 426. This prepares a circuit by which the called 40 line may reverse the charges.

Referring now to the description of the operation by which a time charge is assessed to the meter on the calling line, it will be recalled that the response of the called party brought about 45 a reversal of battery over the conductors 397 and 398. This reversal of current flow brings about the operation of the electro-polarized relay 254 in the repeater R at the local exchange. The relay 254 upon operating completes a circuit for 50 the relay 250 at armature 273 and at the armatures 271 and 272 changes the bridge across the talking conductors 280 and 281 to exclude the normally closed springs controlled by armature 269. The relay 250 upon operating the armature 262 completes a high impedance bridge 55 across the trunk conductors 280 and 281 and at the armatures 260 and 261 reverse the connections of the line relay 251 with respect to the trunk conductors 197 and 198. The bridge 60 across the trunk conductors now extends from trunk conductor 280, armature 266 and its front contact, front contact and armature 271 winding a polarized relay 254, front contact and armature 262, both windings of impedance relay 258, armature 272 and its front contact to trunk conductor 281. This bridge circuit is of relatively high impedance so as not to affect the conversational circuit. The reversal of the battery 65 connections over conductors 197 and 198 brings the current flow in the lower winding of the electric polarized relay 127 in the same direction as the current flow in its upper winding and this relay is energized to complete a circuit for 70 the relay 126 at armature 143 and to complete 75 a circuit at armature 145 for the motor magnet

of the timing switch RS-1. The circuit for energizing the motor magnet 158 extends from ground upon the release trunk by way of armature 145 and its front contact, bank contact with which the switch wiper 161 is in engagement in 5 normal position of the switch wipers, said wiper, back contact and armature 163 and motor magnet 158 to battery. The slow acting relay 126 upon operating prepares a circuit at armature 142 for the relay 125. 10

The motor magnet 158 is operated over the above traced circuit to advance the switch wipers 159 to 162 of the timing switch RS-1 associated with the selector S, one step into engagement with the second set of bank contacts. The 15 movement of the switch wiper 161 opens the previously traced circuit for the motor magnet 158. However, the operation of the switch wipers and more particularly the switch wiper 162 into engagement with the second set of bank contacts 20 prepares a circuit for the operation of the motor magnet 158 which includes the interrupter or commutator 173 mounted upon the shaft 174 and connected to ground. As explained before, the shaft 174 is being constantly 25 rotated at a predetermined speed. All bank contacts, except the last four and the first one of the rotary switch RS-1 are multiplied together and connected to the armature 171 of the relay 170. Consequently, as the shaft 174 is rotated, 30 ground is periodically connected to the winding of the motor magnet 158, which is periodically operated to advance the switch wipers 159 to 162 over the bank contacts. The advancement of the switch wipers of the rotary switch RS-1 35 continues as a result of the impulsive circuit to motor magnet 158 described, until the switch wipers are brought into engagement with the fourth from the last set of bank contacts, whereupon the impulsive circuit for the motor magnet 40 158 is transferred to the commutator 178 mounted upon the shaft 181. This shaft is moving at a slower speed than shaft 174 and consequently the switch wipers are not advanced so rapidly. Furthermore, during one revolution of the commutator 178, only one circuit is completed for 45 the motor magnet 158, which further delays the advancement. When the switch wipers are brought into engagement with the third from the last set of bank contacts there will be a 50 tone connected to the talking circuit over a path which extends from the tone machine by way of the conductor 191, commutator 176, condenser 182, bank contact with which the switch wiper 160 is in engagement, armature 166 and 55 its back contact, condenser 167, to the talking circuit. The tone machine connected to the conductor 191 gives a distinctive tone slightly in advance of the metering charge to apprise the calling party that a charge is about to be made. 60 When the switch wipers of the switch RS-1 are brought into engagement with the second from the last set of bank contacts there is a circuit completed for the relay 170 over a path which 65 may be traced from the metering battery B through a commutator 177 when in the proper position, wiper 159, second from the last bank contact, and upper winding of relay 170 to ground. The relay 170 is energized over this 70 circuit to establish a locking circuit through its lower winding to ground upon the release trunk conductor at armature 180 and to disconnect the bank contacts that control the periodic operation of the motor magnet 158 of the rotary switch RS-1 from the commutator 173 and connects 75

them to the commutator 172. The purpose of this operation is for the reason that the usual practice in assessing telephone charges is to assess an initial charge for an interval of time; 5 thereafter to assess a charge for every minute or a shorter interval of time. By reason of the number of segments on the commutator 172 the switch wipers are stepped more rapidly to accomplish the difference in charges. The operation 10 of the switch wiper 168 into engagement with the second from the last bank contacts connects the tone from the tone machine connected to the conductor 199 to the talking circuit whereby the calling subscriber is apprised that his 15 meter is being operated to assess the charge. The motor magnet 158 continues to be operated periodically by reason of the ground connection through the commutator 178. The purpose of switching the control of the motor magnet during 20 the last four steps of the metering switch RS-1 is to provide for uniform operation of the switch over the last segments. This permits the tones to be applied to the talking circuit for a uniform interval, irrespective of the speed of 25 operation of the motor shaft 174.

It should be mentioned at this time that the speed of the motor shaft 174 may vary in accordance with the time of day, or in accordance with traffic conditions in the exchange so 30 as to provide a greater charge in the event that the call is made during a peak load or during ordinary load.

When the switch wipers are stepped into engagement with the last set of bank contacts 35 there is a metering circuit completed for energizing the meter 107 of the calling line. This circuit may be traced from the metering battery B through the commutator 177, wiper 159, last bank contact, back contact and armature 140, 40 bank contact 131, wiper 110, front contact and armature 115 and meter 107 to ground. The meter 107 is operated over this circuit to assess a charge against the calling line.

Since an inter-office trunk line is being employed in this connection, the called subscriber is in a different zone from the calling subscriber and it is necessary to arrange the meter charges to provide a different charge in this class of connection as before described. It will be seen 45 that there is a circuit completed in parallel with one that operates the meter 107 that extends from the metering battery B, wiper 159, 25th or last bank contact, back contact and armature 140, armature 144 and its front contact, wiper 135, bank contact 184, conductor 195, relay 200 50 of rotary timing switch RS-5, wiper 212 and first bank contact 215 to ground. The relay 200 is energized over this circuit in parallel with the meter 107 and operates to complete a circuit for the relay 201 at armature 204 and to open a point in the impulsion circuit at armature 205. The relay 201 upon operating, establishes a locking circuit for itself at armature 206, extends the metering circuit to the motor 55 magnet 218 at armature 207, prepares a metering circuit at armature 208 and at armature 209, disconnects battery from the bank contacts accessible to the wiper 216 other than the first one. The motor magnet 218 is also operated 60 over the metering circuit but since the switch wipers 212 to 214, inclusive, are not actuated until the motor magnet 218 de-energizes, no operation occurs. When the metering circuit is 65 opened at the rotary switch RS-1, the circuit for the slow acting relay 200 and the motor 70

magnet 218 is opened and they are de-energized. The de-energization of the relay 200 occurs after a short interval of time and prepares an impulsive circuit for the motor magnet 218. The motor magnet 218 is de-energized immediately 5 upon the opening of the metering circuit to advance the switch wipers 212 to 214, inclusive, one step into engagement with their second set of bank contact. The interrupter 225, after a short interval of time, completes another circuit 10 for the meter 107 and for the motor magnet 218 in parallel. This metering circuit may be traced from the metering battery B-1, armature 205, and its back contact, armature 208 and its front contact, front contact and armature 207, metering conductor 195, bank contact 184, switch wiper 135, front contact and armature 144, bank contact 121, switch wiper 110, front contact and armature 115 and meter 107 to ground. The meter 107 is operated to assess an additional 15 charge. The motor magnet 218 is operated to advance the switch wipers 212 to 214, inclusive, another step. At each revolution of the interrupter 225, the metering battery brings about the operation of the meter on the calling line 20 and the operation of the motor magnet 218. This continues until the proper charge is assessed on the meter 107 associated with the calling line. At this time the wiper 214 of the rotary switch RS-5 will engage a bank contact 25 to which ground is connected through the distributing frame DF. A circuit is thereupon completed for the relay 202. The relay 202 is energized to open the locking circuit of the relay 201. The relay 201 is de-energized to open the 30 metering circuit and the stepping circuit at armatures 207 and 208, respectively, and to complete a release circuit at armature 209. This release circuit may be traced from battery by way of armature 209 and its back contact, bank contact with which the switch wiper 213 is in engagement, back contact and armature 211 and motor magnet 218 to ground.

The motor magnet 218 is energized and since it interrupts its own circuit at armature 211, it 45 is repeatedly operated as a buzzer to bring the switch wipers 212 to 214, inclusive, into engagement with the first set of bank contacts. At this time, the circuit of the motor magnet is opened since battery is not connected to the bank contact 216 and the rotation of the rotary switch RS-5 will cease.

It will be seen that each time the calling subscriber's meter 107 is operated by the timing switch RS-1, the rotary switch RS-5 will be 50 operated to assess an additional charge depending upon the inter-exchange trunk line employed. That is, by connecting ground to any particular terminal on the distributing frame DF, the rotary switch RS-5 may be stopped at any point in its operation so that the charge assessed against the calling line can be readily altered. All the rotary switches such as RS-5 55 associated with trunk lines to common offices will have a predetermined charge to add to the original charge depending upon the exchange or zone to which the call is made.

Obviously, this provision is not needed in local exchange calls when the timing switch RS-1 60 associated with the first selector makes the local time charge. The provision of timing switches RS-1 and RS-5 in the exchange in which the call originates is all the equipment necessary to provide for the charging of the call- 65 70 75

ing subscriber in accordance with the zone in which the called line is located.

Returning now to the description of the operation of the rotary switch RS-1, it will be understood that during its operation which has been initiated by the removal of the receiver at the called telephone, subscribers may carry on their conversation. The operation of the rotary switch RS-1 continues past the last set of bank contacts and the switch wipers 159 to 162 in their continued rotation are brought into engagement with their normal set of bank contacts. The operation of the switch RS-1 continues identically the same manner as described with the same results. Its operation during this second revolution is faster than the first by reason of the operation of the relay 170 previously described. The operation of the rotary switch RS-5 is initiated to assess an additional charge each time the meter 107 of the calling subscriber is actuated by the rotary switch RS-1.

In the usual course of events, the operation of the timing switch RS-1 will continue until the calling subscriber replaces his receiver upon the switch hook at the end of the conversation and the meter 107 will be assessed in accordance with the time the telephone has been used and the rate, or rates prevailing during that period of time.

Under these conditions when the calling subscriber replaces his receiver, the line relay 251 in the repeater R is de-energized to open the circuit of the slow acting relay 252 and to open the bridge across the trunk conductors 280 and 281.

The opening of the bridge across the trunk conductors 280 and 281 brings about the de-energization of the line relay 404 in the connector C and this relay will be de-energized to remove ground from the release conductor 396 whereby the switching relay 315 of the incoming selector S-1 is de-energized. The de-energization of the switching relay 315 brings about its release in the manner already described.

In the repeater R, the de-energization of the slow acting relay 252 brings about the removal of ground from the release trunk conductor 196 whereby the switching relays 128 and the selector S and 108 in the line switch

LS are de-energized. The de-energization of the relay 128 in the selector switch S brings about its release in the same manner as has already been described. In order to restore the wipers of the rotary switch RS-1 to normal position, when the relay 128 is deenergized, there is a circuit completed which extends from ground by way of armature 151 and its back contact, armature 164 and its back contact, bank contacts engaged by the switch

wiper 161, back contact and armature 163 and motor magnet 158 to battery. This circuit serves to bring about the continued operation of the motor magnet 158 to advance the switch wipers into their normal position. The removal of ground from the release conductor also opens the locking circuit of the relay 170 and this relay is de-energized to restore a connection of the commutator 173 and its associated bank contacts.

The rotary switch LS is restored to normal in the same manner as previously described. In the event the rotary switch RS-5 is not restored to normal at the time the calling subscriber hangs up, its release occurs in the manner described following the de-energization of the relay 202.

In the connector switch C, if the called subscriber has not yet placed his receiver upon the switch hook, the circuit of the release magnet is maintained open and the connector is not released until the called subscriber hangs up his receiver. The rotary switch RS-2 is, however, restored to normal by the connection of ground to the bank contacts accessible to wiper 475, which brings about the continued operation of the motor magnet 464 in an obvious manner. The switch wipers 473 to 476, inclusive, are rotated to their normal position. When the called subscriber hangs up there is a release circuit established for bringing about the release of the connector C, which may be traced from ground by way of armature 431, and its back contact, armature 433 and its back contact, armature 423 and its back contact, off-normal spring 457 and its working contact, back contact and armature 471, and release magnet 411 to battery. The release magnet 411 is operated over this circuit to restore switch wipers of the connector switch to normal. The de-energization of the relay 400 responsive to the called subscriber replacing his receiver brings about the de-energization of the relays 407 and 410 and these relays retract their armatures to restore their respective circuits to normal.

Attention is directed to the fact that the selector switch S cannot be restored to normal until the rotary switch RS-1 is in normal position though if the calling subscriber replaces his receiver upon the switch hook immediately after the called party answers and before a charge is made or responsive to his initial tone indicating a charge about to be made, the meter 107 will not be operated. This provision is made so that there will be no charge in the event a wrong number is obtained.

Attention is also directed to the fact that if the called subscriber does not immediately replace his receiver and the connector remains in operated position, ground is connected by way of armature 423 and its front contact to the supervisory signal to indicate this fact, and an attendant can remedy the situation, if the condition persists.

It will be assumed that during the progress of the call between the sub-stations T and T-1, as before described, that the called party desired to have the charge assessed against his line and not against the calling line.

Under these conditions, the circuit, it will be assumed, is established as before, employing the line switch LS, selector S, repeater R, incoming selector S-1 and connector C. It will be recalled that immediately upon the called subscriber at station T-1 removing his receiver the relays 400, 401 and 403 in the connector and the relays 126 and 121 in the selectors were operated. As a result of these operations the rotary switches RS-1 and RS-2 associated with the selector S and connector C respectively, begin to operate in the same manner as described. The charge will be against the calling line until the subscriber at sub-station T-1 depresses his push button 566. When this occurs the shunt around the resistor 555 included in the line circuit is removed and the marginal relay 401 in the connector C is de-energized. By the de-energization of this relay a point in the circuit of the lower winding of the differential relay 403 is opened and a circuit is provided for the upper winding of the differential relay 403, provided of course the metering switch or time switch M-1 is in the 75

proper position with the relay 402 energized. The circuit for the upper winding of the differential relay 403 extends from ground by way of front contact and armature 414, front contact and armature 429, armature 422 and its front contact, armature 425 and its back contact, armature 426 and its front contact and upper winding of differential relay 403 to battery. The relay 403 is de-energized since current in both windings 5 oppose. As a result of the de-energization of the relay 403, the connections of the line relay 404 with respect to the trunk conductors 397 and 398, is restored to normal. Another result of the operation of the relay 403 is that an armature 10 429 in the circuit of both windings is opened. By the engagement of armature 430 of the relay 403 with its back contact, there is a circuit completed extending from ground on release trunk conductor 396, armature 430 and its back contact, 15 back contact and armature 477 and relay 463 to battery. The relay 463 is energized to establish a locking circuit for itself at armature 479 to open a point in the circuit of the release magnet at armature 471 to prepare a metering circuit 20 at armature 469 and to prepare a circuit at armature 468 for applying tone to the talking circuit.

As a result of the reversal of connections of the line relay 404 of the connector as described by the de-energization of the differential relay 403, 25 the current flow through the lower winding of the electropolarized relay 127 is again changed through the action of relay 250 in repeater R and opposes the current flow in its upper winding. As a result of this operation, the armatures 143 and 145 of this relay are retracted. The operation of the armature 143 serves to complete a circuit for the relay 125 over a path extending from ground on the release trunk conductor, armature 143 and its back contact, armature 142 and its 30 front contact, and relay 125 to battery. Relay 125 is energized over this circuit to establish a locking circuit for itself at armature 139 to open a point in the circuit extending to the meter of the calling telephone at armature 140 to prepare a point in the release circuit at armature 141 and to open the connection by which tone through the switch RS-1 is applied to the talking circuit at armature 166. As a result of the energization of relay 125 the continued operation of the 35 rotary switch RS-1 is ineffective. The operation of the relay 125 also opens the metering circuit extending back to the switch RS-5 so that all further charges from this switch will cease.

When the called subscriber releases the push button 566, a shunt is again replaced around the resistor 555 and the relay 481 in the connector is again operatively energized to attract its armatures 424, 425 and 471. The operation of its armature 425 opens a point in the circuit of the upper winding of the differential relay 403, while the operation of the armature 471 opens a point in the circuit of the relay 463. The operation of the armature 424 serves to again establish a circuit for the lower winding of the differential relay 403, whereby the connections of the line relay 404 with respect to the talking conductors 397 and 398 is again reversed. The reversal of these connections again brings about the energization of the electropolarized relay 127 in the selector S 40 through the action of relay 250 in the repeater R, but its operation has no particular function at this time.

It will be recalled that when the relay 403 was originally energized, the motor magnet 464 of the 45 rotary switch RS-2 was operated and that the

wipers of the rotary switch RS-2 were advanced one step into engagement with the second set of bank contacts. By this advancement the original circuit for the motor magnet is broken at the wiper 475 and another circuit was established for this magnet, which extends by way of the wiper 476, second set of bank contacts, armature 467 and its back contact and commutator 485 on the shaft 489 to ground. The motor magnet is periodically operated by the operation of the commutator 485 advancing the switch wiper step by step at a definite rate of speed. When the switch wipers are brought into engagement with the fourth from the last set of bank contacts, the circuit for operating the motor magnet above described is switched to the commutator 487 on the shaft 488, which moves uniformly. When the switch wipers are advanced into engagement with the third from the last set of bank contacts, if the subscriber of the called sub-station has depressed his push button at this time to bring about a reversal of charges, a tone from the tone machine 480 is applied to the talking circuit over a path that may be traced from the tone machine, commutator 483, third from the last set of bank 50 contacts, wiper 474, front contact and armature 468, condenser and thence to the talking circuit. This tone apprises the subscribers that a charge is about to be made. The tone may be of different pitch than the tone connected either to the conductors 190 or 191 associated with the selectors, and apprises the subscribers the charge is to be made against the called telephone. When the switch wipers are advanced into engagement with the second from the last set of bank contacts, the tone from the tone machine 481 is connected to the talking circuit and will apprise the subscribers that a charge is being made against the called telephone. As before described, the shaft 488 of the metering equipment M-2 may be driven at varying rates, depending upon the time or traffic conditions to make a charge in accordance with the amount of traffic in the exchange or in accordance with the time of day.

When the switch wiper 473 is brought into engagement with the last set of bank contacts there is a metering circuit completed, which extends from the metering battery B-1, commutator 484, wiper 473, last bank contact, front contact and armature 469, front contact and armature 478, front contact and armature 445, wiper 414, bank contact 492, conductor 500, and meter 552 associated with the line switch of the called telephone to ground. The meter 552 is operated to assess the charge against the called telephone.

When the switch wiper 473 was in engagement with the second from the last set of bank contacts there was a circuit completed for the upper winding of the relay 462. The relay 462 is energized to establish a locking circuit for itself at armature 466, which extends to release trunk ground, and connects the impulsive circuit through the commutator 486 to provide that faster operation of the timing switch RS-2 during its second operation may be had. So long as the subscribers at sub-stations T and T-1 are in communication, the time charge will be assessed against the called telephone in accordance with the traffic conditions.

In order to make an additional charge against the called line in this particular instance where the call originates in a different exchange, there is a rotary metering switch RS-6 associated with the incoming trunk line. When a circuit is completed for operating the meter 552 in the man-

ner described, another circuit is completed over the metering trunk conductor which may be traced from the metering battery commutator 484, wiper 473, last bank contact, front contact and armature 469, armature 478 and its front contact, trunk conductor 395, bank contact 340, wiper 336 of selector switch S-1, armature 314 and its front contact, slow acting relay 350, wiper 362 and bank contact 365 to ground, the slow acting relay 350 is energized to complete a circuit for the relay 351 at armature 354 and to open a point in the metering circuit at armature 355. The relay 351 is energized to establish a locking circuit for itself at armature 356 to complete a circuit for the motor magnet 368 at armature 357 to prepare a metering circuit at armature 358 and to open a point in the release circuit at armature 359. When the relay 402 of the connector C was energized upon connection being made with the called line, a circuit was completed in parallel with the meter 552 extending to the line relay 350 of the switch RS-6. However, by reason of the high resistance of the relay 402 included in this circuit the relay 350 was not energized. When the above traced metering circuit is opened, the circuit of the slow acting relay 350 and the motor magnet 368 is opened and they de-energize. The de-energization of the motor magnet 368 serves to advance the switch wipers 362 to 364, inclusive, into engagement with the second set of bank contacts. The movement of the switch wiper 362 out of engagement with its normal bank contact 365 opens another point in the circuit of the slow acting relay 350. The slow acting relay 350 is de-energized after a short interval of time to open the original circuit for the relay 351 at armature 354 and to prepare a new metering and impulsive circuit at armature 355. For each revolution of the interrupter 375, a battery is connected to the motor magnet 368 to bring about its interrupted operation and the advancement of the switch wipers 362 to 364, inclusive. At each revolution of the interrupter 375, there is an additional circuit completed for the meter 552 associated with the called line over a path that may be traced from the metering battery through the interrupter 375, armature 355 and its back contact, armature 358 and its front contact, front contact and armature 357, front contact and armature 314, wiper 336, bank contact 340, metering conductor 395, front contact and armature 445, wiper 416, bank contact 492, trunk conductor 500 and meter 552 to ground. The meter 552 is thus operated to assess an additional charge against the called line in accordance with the zones that the subscribers at sub-stations T and T-1 are located in.

When the proper charge is assessed, the switch wipers 362 to 364, inclusive, will be advanced to the set of bank contacts at which the wiper 364 engages a ground potential through the distributing frame DF-1. At this time there will be a circuit completed for the relay 352 which, upon operating, opens the locking circuit of the relay 351. The latter relay is de-energized to open the metering circuit at armature 357 to open the impulsive circuit at armature 358 and to complete a release circuit at armature 359. This release circuit brings about the rapid step by step action of the motor magnet 368 until the switch wipers 362 to 364, inclusive, are advanced to their normal position.

In this manner, after each charge is assessed against the calling line from the rotary switch RS-2 associated with the connector C, additional

charges are assessed against the called line depending upon the zones that the subscribers are located in.

Obviously, by means of the distributing frame DF-1, any assessment desired may be made against the called line and it may be the same or vary from that assessed against the calling line in the manner described should it be desired to penalize the called subscribers employing this service.

It will be seen that there is an additional charging switch associated with each inter-office trunk line at both the outgoing and incoming ends and these switches will function to add additional charges to the calling or called lines, depending upon the zones that the two subscribers are in.

It will be perfectly obvious that if the trunk lines should be of the two-way type that no additional rotary charging switches need be associated with them. That is, in two-way trunk lines the rotary charging switches into each exchange will function equally well on calls in either direction. These additional charging switches may well be termed "surcharge".

It will be seen that this additional zone metering charge is directly variable in accordance with the time of day and the various conditions affecting local charges as already explained.

In local calls, it will be obvious, of course, that no surcharges will be necessary but that the subscribers may reverse the time charges from the calling to called telephone, as desired.

When the conversation is finished, the subscribers will replace their receivers upon their respective switch hooks and the various switches employed in the connection will be restored to normal in the manner already described.

Attention is directed to the fact at this time that in the event the called subscriber hangs up and the calling subscriber maintains the connection, the de-energization of the relay 400 responsive to the replacement of the switch hook at the called telephone opens the metering circuit at armature 478 so that the calling subscriber cannot make an unfair charge against the called subscriber.

When the conversation is terminated, the subscribers will replace their receivers upon their respective switch hooks. As a result of the replacement of the receiver at the calling station, the line relay 404 in the connector C will be de-energized and the slow acting relay 405 will be de-energized a short time thereafter to remove ground from the release trunk conductor 396, thereby bringing about the release of the incoming selector S-1 in the manner already described.

At the local exchange, the line relay 251 of the repeater R is de-energized to open the circuit of the slow acting relay 252 which is de-energized to remove ground from the release trunk conductor 196, thereby bringing about the release of the line switch LS, selector S and the restoration to normal of the timing switch RS-1 individual to the selector in a manner similar to that already described. The de-energization of the relay 405 in the connector C also causes the timing switch RS-2 to be restored to normal by applying ground to the bank contacts accessible to the wiper 475 of the rotary switch RS-2. This ground connection causes the motor magnet 464 to operate to rotate the switch wipers 473 to 476, inclusive, to normal position. When the called subscriber at sub-station T-1 hangs up, the circuit for the release magnet 411 is completed and the

connector switch C is released in a manner similar to that already described.

From the foregoing it will be seen that there is a time charge made against the calling line upon the response of the called line under the control of a rotary switch, such as RS-1 individual to the selector used. It is desirable that the rotary switches such as RS-1 be rotated relatively rapidly under the control of the impulging device 173, somewhat more rapidly under the control of the impulging device 172. This arrangement should be so that the initial rotation of the rotary switch RS-1 will occur in approximately twenty seconds, though this period may be varied as desired, and that the second rotation will occur at a relatively faster speed. This provision should be made in order that the calling subscriber cannot hold a conversation with the called subscriber for any particular period of time for the charges made. The meters such as 101 and 552 can be regulated to make the proper charge for the usual number of operations.

In a like manner the switches such as RS-2 associated with the connector should be arranged to rotate at substantially the same speed as the timing switches RS-1. The surchargers RS-5 and RS-6 are operated to bring about the additional zone charge against the calling or called subscribers in the manner described immediately following the assessment of the usual charge against either calling or called telephone in the manner described.

It will be seen that the charges made to the called subscriber's line at his option will be in accordance with the time the telephone talking circuit is in use, the time of day at which the call is made and the rate prevailing at that time and the zones in which the subscribers are located. Attention is also directed to the fact that means are provided for indicating to the subscriber, irrespective of their zones, which line the charge is being assessed against and also when the charge is made.

The telephone sub-station T-2 is somewhat modified so that instead of the push button such as 557 removing the short circuit about a resistor, the depression of the push button grounds one side of the line. This grounding may be employed to operate a relay such as 401 in the connector of the differential type instead of a marginal relay in an obvious manner. Under these conditions, the results will be identical with those described.

In a metering system such as has been described it is desirable that certain telephone lines such as those belonging to the telephone company be arranged for a free charge, so that no charge will be made to the calling party in the event connection is made with any of these lines. In order to accomplish this result, the line extending to a free telephone is provided with the relay equipment associated with the line switch such as RS-4. The bank contact which ordinarily would be connected to the meter in the connectors such as 493 is connected through a resistor to ground.

A short description of the manner in which a call is made to the line of this character and the functioning of equipment under these conditions, and particularly the difference between this kind of a call and a regular call will now be described. In establishing the connection from the calling telephone T to the called telephone T-3 of the free class, line switch RS of the calling line and a

selector such as S, repeater R, selector S-1 and a connector such as C, will be operated in identically the same manner as before described to establish the connection. It will be assumed that the selector switch S, repeater R, selector S-1 and the connector C are the ones employed to establish the connection. Connector switch C will be operated so as to bring its wipers 416 to 419, inclusive, into engagement with the bank contacts 493, 497 and 495 and 499, respectively. The bell 10 at the substation T-3 will be operated periodically to summon the subscriber thereto. When the party at the telephone T-3 removes his receiver from the switch hook, the ring cut-off relay 467 is energized to establish a locking circuit for itself at armature 437 and connect the called line to battery through the backbridge relay 400 and the marginal relay 401. Both these relays are operated with the same results as before. The differential relay 403 is also energized to reverse the connections of the line relay 404 with respect to the trunk conductors 397 and 398. It will be seen that the relay 519 is included in the line circuit of the called telephone in parallel with a non-inductive resistance so as to provide a clear path for voice currents, and partially to short circuit the relay 519 when ringing current is applied. Relay 519 is adjusted not to respond to ringing current, however, the relay 519 is energized in series with the relays 400 and 401 of 30 the connector. The relay 519 upon operating completes a circuit for the slow to operate relay 518, and the relay 518 is made slow to operate to give the relays 400 and 401, as well as the relay 403, time to operate before this relay is energized. The 35 operation of the relay 518 serves to complete a circuit for the relay 517 at armature 533 and to open the short circuit around the resistor 536 at the armature 535. The removing of the short circuit around the resistor 536 includes this resistor 40 in the circuit and permits the marginal relay 401 in the connector C to de-energize to retract its armatures. The relay 517 upon energizing, opens a point in the circuit of the relay 518 at armature 531 and completes a locking circuit for 45 itself at armature 532 to ground upon the release trunk conductor 506. The relay 518 is de-energized after an interval of time to open the original energizing circuit of the relay 517 and to again short circuit the resistor 536. 50

In the connector switch C the relay 401 upon de-energizing, completes a circuit for the upper winding of the differential relay 403. The differential relay 403 retracts its armatures again to reverse the connections of the line relay 404 with 55 respect to the trunk conductors 397 and 398, thereby bringing about the retraction of the armature 273 of the electropolarized relay 254 in the repeater R and this brings about the de-energization of the relay 250 and the consequent reversal 60 of the connections of the line relay 251 with respect to the trunk conductors 197 and 198, thereby bringing about the energization of the relay 125 in the selector switch S. The operation of this relay renders the functioning of the timing switch RS-1 individual to the selector ineffective, it being remembered that this switch was started by the operation of the electropolarized relay 127 responsive to the first reversal of current over the conductors. The operation of the differential 70 relay 403 brings about the energization of the relay 463 and brings the timing switch RS-2 into play. However, since the metering wiper 414 extends to ground through a resistor by way of the bank contact 493, the metering switch RS-2 is 75

ineffective to assess any charge, there being no meter connected with the telephone T-3, as it is an official or free telephone. In this manner, no charge is made to the calling subscriber when he calls a free telephone number.

When the conversation is terminated the connection is released in a manner similar to that already described.

It is possible in a telephone system of this character that some of the lines other than company lines may not be provided with meters, but be operating on a flat rate basis. In this instance there will be no meter connected to this class of lines. The meter bank contacts 493 in the various connectors having access to this class of lines are simply left open. The purpose of leaving these bank contacts open is to prevent the called party exercising any control whatsoever over the metering charge. It will be seen that if the bank contact such as 493 is left open there is no circuit that may be completed for the relay 402, which controls the de-energization of the differential relay 403, the relay 350 being of sufficiently high resistance to prevent the operation of the relay 402. Consequently, a called party having such service could not by any manipulation or appliance on his telephone line cause the disconnection of the metering charge to the calling party, which he might do were it not for this provision.

From the foregoing, it will be obvious also that a certain amount of the charge may be assessed against the calling line and thereafter further charge may be made against the called line, depending upon the time at which the called party exercises his reverse control.

The clock switch M-1 provides means by which, during certain hours of the day, a certain group of lines or all lines in the exchange may not have this reverse service.

It will be obvious that the surchargers or rotary timing switch may be used where no reverse metering is employed for the purpose of bringing about a toll charge where toll calls are made or where calls are made to subscribers in exchanges in different zones than that of the calling subscriber. A very great advantage of this construction is that the surcharging switches may be inserted at any point in the connection in association with any other class of switches to add any desired number of impulses to an impulse train and that only one trunk wire is necessary for its functioning. This greatly reduces the amount of equipment ordinarily required for zone metering purposes and particularly where time charges are made. Ordinarily to make proper zone meter charges, it is necessary to employ some artificial means such as a director or translator whose cost is large both as to original cost and maintenance. However, while employing the rotary switches or surchargers at the desired point in the connections, the regular exchange equipment may be employed and at the same time, all advantages as to flexibility may be obtained. Attention is directed to the fact that the surchargers cannot function until the local metering charge is made and that there can be no interference between them.

Having described certain specific embodiments of my invention, I am aware that many changes, departures and deviations may be made therefrom, without departing from the spirit and scope thereof, as indicated in the appended claims:

I claim:

1. In an automatic telephone system, the combination of telephone lines terminating in a plurality of exchanges, a metering device associated with each telephone line, means including automatic switches and two-conductor trunk lines for establishing a connection between a calling and called one of said lines, said trunk lines including only two conductors, and means controlled from one of the telephone lines after the connection is established for operating the metering device on either the calling or called lines as a result of the establishment of the connection. 5

10 15 20 25

2. In an automatic telephone system, the combination of telephone lines terminating in a plurality of exchanges, a metering device associated with each telephone line, means including automatic switches and two-conductor trunk lines for establishing a connection between a calling line in one exchange and a called line in another exchange, said trunk lines including only two conductors, and means controlled from one of the telephone lines after the connection is established for operating the meter on the calling or called line over a part of said connection. 25

30 35 40

3. In an automatic telephone system, the combination of telephone lines terminating in a plurality of exchanges, a metering device associated with each telephone line, means including automatic switches and two-conductor trunk lines for establishing a connection between a calling line in one exchange and a called line in another exchange, said trunk lines including only two conductors, and means controlled from one of the telephone lines after the connection is established for operating the meter on the called line as a result of the establishment of the connection between the lines. 35

40 45 50 55

4. In an automatic telephone system, the combination of telephone lines terminating in a plurality of exchanges, a metering device associated with each telephone line, means including automatic switches and two-conductor trunk lines for establishing a connection between a calling line in one exchange and a called line in another exchange, said trunk lines including only two conductors, and means for operating the meter on the called line under the control of the subscriber thereat as a result of the establishment of the connection. 50

55 60 65

5. In an automatic telephone system, the combination of telephone lines terminating in a plurality of exchanges, a metering device associated with each telephone line, means including automatic switches and two-conductor trunk lines for establishing a connection between a calling line in one exchange and a called line in another exchange, said trunk lines including only two conductors, and means for periodically operating the meter on either the calling or called line according to the period of the connection while said connection is maintained. 60

70 75 80 85

6. In an automatic telephone system, the combination of telephone lines terminating in a plurality of exchanges, a metering device associated with each telephone line, means including automatic switches and two-conductor trunk lines for establishing a connection between a calling line in one exchange and a called line in another exchange, said trunk lines including only two conductors, and means controlled from one of the telephone lines after the connection is established for periodically operating the meter on the called line while said connection is maintained. 70

7. In an automatic telephone system, the com- 75

- combination of telephone lines terminating in a plurality of exchanges, a metering device associated with each telephone line, means including automatic switches and two-conductor trunk lines for establishing a connection between a calling line in one exchange and a called line in another exchange, said trunk lines including only two conductors, and means for periodically operating the meter on either the calling or called line while 5
 10 said connection is maintained at the option of the subscriber on the called line.
8. In an automatic telephone system, the combination of telephone lines terminating in a plurality of exchanges, a metering device associated with each telephone line, means including automatic switches and two-conductor trunk lines for establishing a connection between a calling line in one exchange and a called line in another exchange, said trunk lines including only two conductors, means for operating the meter associated with the calling line during a portion of the time that the connection is established, and means for operating the meter on the called line during another portion of the time that the connection is maintained. 15

 25
9. In an automatic telephone system, the combination of telephone lines terminating in a plurality of exchanges, a metering device associated with each telephone line, means including automatic switches and two-conductor trunk lines for establishing a connection between a calling line in one exchange and a called line in another exchange, said trunk lines including only two conductors, means for operating the meter associated with the calling line during a portion of the time that the connection is established, and means for operating the meter on the called line during another portion of the time that the connection is maintained, said means being controlled from the called line. 30
 35
 40
10. In an automatic telephone system, the combination of telephone lines terminating in a plurality of exchanges, means including automatic switches for establishing a connection between a calling line in one exchange and a called line in another exchange, and means for signaling the subscribers on said lines to indicate the line that is assessed with the charge. 45
 50
11. In an automatic telephone system, the combination of telephone lines terminating in a plurality of exchanges, a metering device associated with each telephone line, means including automatic switches and two-conductor trunk lines for establishing a connection between a calling line in one exchange and a called line in another exchange, said trunk lines including only two conductors, means for operating the meter associated with the called line periodically while said connection is maintained, and means for varying the periods of time between said meter operations. 55
 60
12. In an automatic telephone system, the combination of telephone lines terminating in a plurality of exchanges, a metering device associated with each telephone line, means including automatic switches and two-conductor trunk lines for establishing a connection between a calling line in one exchange and a called line in another exchange, said trunk lines including only two conductors, means for operating the meter associated with the called line periodically while said connection is maintained, and means for varying the periods of time between said meter operations depending upon the time of day during which the connection is established. 65
 70
 75
13. In an automatic telephone system, the combination of a pair of automatic telephone exchanges, telephone lines terminating in each exchange, a metering device associated with each line, means including automatic switches for establishing a connection between a line in one exchange and a line in another exchange, means for operating the meter associated with the called line periodically while said connection is maintained, and means for varying the periods of time between meter operations depending upon whether the call is from the lines in the same exchange or between exchanges to make a charge on the meter which varies depending upon whether the call is between lines in the same or different exchanges. 5
 10
 15
14. In an automatic telephone system, the combination of a pair of telephone exchanges, telephone lines terminating in each exchange, a metering device associated with each line, means including automatic switches and two-conductor trunk lines for establishing a connection between a line in one exchange and a line in another exchange, said trunk lines including only two conductors, means for operating the meter on either of the calling or called lines as a result of the establishment of the connection at the option of the subscriber on the called line, and means operative during certain intervals of time for preventing the operation of the meter on the called line. 20
 25
 30
15. In an automatic telephone system, the combination of a pair of telephone exchanges, telephone lines terminating in each exchange, a metering device associated with each line, means including automatic switches and two-conductor trunk lines for establishing a connection between any two of said lines, said trunk lines including only two conductors, and means for operating the meter associated with either line at the option of the subscriber on the called line. 35
 40
16. In an automatic telephone system, the combination of a pair of telephone exchanges, telephone lines terminating in each exchange, a metering device associated with each line, means including automatic switches and two-conductor trunk lines for establishing a connection between any two of said lines, said trunk lines including only two conductors, and means controlled from one of the telephone lines after the connection is established for operating the meter associated with either line as a result of the establishment of the connection. 45
 50
17. In an automatic telephone system, the combination of a pair of telephone exchanges, telephone lines terminating in each exchange, a metering device associated with each line, means including automatic switches and two-conductor trunk lines for establishing a connection between any two of said lines, said trunk lines including only two conductors, and means for periodically operating the meter associated with the called line while the connection between the lines is maintained. 55
 60
 65
18. In an automatic telephone system, the combination of a pair of telephone exchanges, telephone lines terminating in each exchange, a metering device associated with each line, means including automatic switches and two-conductor trunk lines for establishing a connection between any two of said lines, said trunk lines including only two conductors, means for operating the meter associated with the called line periodically while said connection is maintained, and means for varying the periods of time between said 70
 75

meter operations depending upon the traffic load of the telephone system.

19. In an automatic telephone system, the combination of a pair of telephone exchanges, telephone lines terminating in each exchange, a metering device associated with each line, means including automatic switches for establishing a connection between any two of said lines, means for operating the meter associated with either line at the option of the subscriber on the called line periodically while the connection is maintained, and means for varying the meter operation depending upon whether the lines are located in the same exchange or different exchanges to make a charge on the meter which varies depending upon whether the call is between lines in the same or different exchanges.

20. In an automatic telephone system, the combination of telephone lines terminating in an automatic exchange, a metering device associated with each line, trunk lines extending from the exchange to other exchanges, means for establishing connections between said lines without a trunk line or between one of the lines and one of the trunk lines, a control device included in said connection when a connection only is made with any of said trunk lines, means for operating the meter on the calling line as a result of the establishment of a connection whether with or without a trunk line, and means controlled by the control device for further operating the meter associated with the calling line only when a connection includes a trunk line.

21. In an automatic telephone system, telephone lines, a metering device associated with each line, means including automatic switches and two-conductor inter-office trunks for establishing connections between said lines, said trunks including only two conductors, a meter control device with each trunk, and means for connecting a said control device to the meter on the calling line in the establishment of certain of said connections only when using an inter-office trunk.

22. In a telephone system, a pair of telephone exchanges, trunk lines connecting said exchanges, a control device associated with each of said trunk lines in each of said exchanges, automatic switches in each exchange for establishing connections between telephone lines in one exchange and the telephone lines in the other exchange over one of said trunk lines, means for operating the meter associated with the called line as a result of the establishment of the connection and means operative from said control device for again operating the meter on the called line.

23. In a telephone system, telephone lines, automatic switches for establishing connections between said lines, a metering device associated with each of said lines, a timing device for operating the meter on the called line periodically while the connection between lines is maintained, a control device, and means responsive to the operation of the meter on the called line for causing the control device to reoperate the meter on the called line.

24. In an automatic telephone system, the combination of telephone lines terminating in automatic exchanges, a metering device associated with each line, trunk lines extending between exchanges, means including automatic switches for establishing connections between said lines or between one of the lines and one of the trunk lines, a control device included in said connection only when a connection is made with one of said

trunk lines, a timing device for operating the meter on the calling line periodically while the connection is maintained, and means for causing the control device to re-operate the meter on the calling line to effect a surcharge dependent upon the time of day in which the call is made. 5

25. In an automatic telephone system, telephone lines terminating in a plurality of exchanges, a metering device associated with each telephone line, directive switches for interconnecting the lines of different exchanges, a trunk line and associated directive switch interposed between the other directive switches in a said connection between lines, and control apparatus individual to the trunk line for operating the called line meter to determine the meter charge according to the trunk line used. 10 15

26. In an automatic telephone system, telephone lines terminating in different exchanges, a metering device for each line, selector and connector switches for interconnecting said lines, trunk lines each having an associated directive switch adapted to be interposed between a selector and connector switch in connections between exchanges, means for operating a line meter responsive to a connection between lines, control apparatus individual to the trunk lines for additionally operating a meter according to the trunk line employed, and means controlled by the called subscriber for determining which line meter is 20 25 30 to be operated.

27. In an automatic telephone system, telephone lines terminating in a plurality of exchanges, a metering device associated with each telephone line, directive switches for interconnecting the lines of different exchanges, a trunk line and associated directive switch interposed between the other directive switches in a said connection between lines, control apparatus individual to the trunk line for determining the meter operation and meter charge, and means controlled by the called subscriber for determining which meter is to be operated. 35 40

28. In an automatic telephone system, telephone lines terminating in different exchanges, a metering device for each telephone line, directive selector and connector switches for interconnecting lines in different exchanges, trunk lines each having an associated directive selector switch, there being different trunk lines for interconnecting lines between different exchanges, meter operating apparatus with each trunk line for operating a line meter according to the trunk line used, and means controlled by the called subscriber for determining which meter is to be operated. 45 50 55

29. In an automatic telephone system, telephone lines terminating in different exchanges, a metering device for each telephone line, directive switches for interconnecting the lines of different exchanges, a trunk line and an associated directive switch interposed between the other directive switches in said connection between lines of different exchanges, a meter control apparatus associated with each end of the trunk line, and means for operating the control apparatus of the trunk line at either one end or the other to operate the calling or called line meter. 60 65

30. In an automatic telephone system, telephone lines terminating in different exchanges, a metering device for each telephone line, directive switches for interconnecting the lines of different exchanges, a trunk line and an associated directive switch interposed between the other directive switches in said connection between lines 70 75

of different exchanges, a meter control apparatus associated with each end of the trunk line, means for operating the control apparatus of the trunk line at either one end or the other to operate the calling or called line meter, and means

controlled by one of the subscribers of the connection for determining which trunk control apparatus is to be used for operating its corresponding meter.

LEONARD WILSON. 5
